UNITED STATES PATENT OFFICE

LESLIE WETHERELL, OF ATTLEBORO, MASSACHUSETTS, ASSIGNOR TO THE MASON BOX COMPANY, OF ATTLEBORO, MASSACHUSETTS, A CORPORATION OF MASSACHUSETTS

CONTAINER AND METHOD OF MAKING SAME

Application filed June 19, 1930. Serial No. 462,374.

This invention relates to containers for articles of jewelry or the like, and pertains more particularly to improvements in the method of making such containers and in the resulting product. The principal objects of the invention are to provide an easy yet efficient process of making a strong and durable container from relatively inexpensive materials which are assembled by simple operations, thereby substantially reducing the cost of manufacture; and to produce an article, so formed, which may be made in a variety of desirable sizes and shapes and which is attractive in appearance without sacrifice of operative efficiency.

My invention is illustrated in the accompanying drawings which show a recommended construction of the improved container and several stages in the method of its manufacture; but it will be understood that the precise details of the method or article herein described may be varied to suit particular purposes without departing from the spirit of this invention as defined in the appended claims.

In the drawings,

Fig. 1 is a perspective view of an opened box made in accordance with the invention;

Fig. 2 is an enlarged section on line 2—2 of Fig. 1;

Fig. 3 is a plan view, to large scale and partly broken away, of three superposed sheets of flexible material used in producing one of the box members of Fig. 1, and constituting the body thereof;

Fig. 4 is a plan view of a frame member employed in the production of the box;

Fig. 5 is a section through the sheets of Fig. 3 indicating in diagrammatic manner, the operation of forming dies thereon;

Fig. 6 is a view similar to Fig. 5 showing the manner of inserting of the frame member within the partially formed sheets, in a subsequent stage of the improved process; and

Fig. 7 is a similar view of another stage in the process, immediately prior to the last operation of the forming dies.

In the particular embodiment of the invention chosen for the purpose of illustration, the improved box or container comprises a

pair of shallow sections or members, indicated generally at 10 and 11 in Fig. 1, of substantially identical construction, pivotally interconnected by hinge members 12 and 13 attached to the respective sections, and preferably having a cooperating spring member 14 of common form which engages the hinge parts and tends to hold the sections either in closed or open position. The bottom section 10 may have an interior pad 15 of plush or other material suitable for the display of an article of jewelry mounted thereon, but it will be evident that a box made in accordance with this invention may be employed for a variety of useful purposes and that its size, shape or appointments for the desired use are not essential to the invention.

The materials employed in making either of the box members 10 or 11 of Fig. 1 comprise a frame member of relatively stiff material such as the flat metal ring 16 (Fig. 4) which assists in shaping and reinforcing the sides of the section; and a body of flexible sheet material preferably consisting of one

or more backing or reinforcing sheets, here shown as the inner sheets 17 and 18 of sized textile fabric, and an outer unsized covering 19 of plush, silk or other material appropriate for the exterior of the container. The

back portion of the metal frame 16 preferably has struck out tongues 20 which extend through openings 21 in the hinge member 12 and are anchored therein, as by folding over the tongue ends, to secure the hinge to the

box section; and the free ends of the frame may be held together in any suitable manner. As the frame is not solely relied upon to produce the ultimate shape of the box, but serves principally as a guide or stiffener upon which

the margins of the fabric body member are folded, the ring 16 need not be rigid circumferentially, and its ends need not be securely united. For example, when the ends 22 overlap each other, as shown in Fig. 4, a paper sleeve 23 may be employed to hold them in proper relation during the formation of the box member.

The principal feature of my improved process resides in the employment of sized

fabric for the backing sheets 17 and 18 of the box body, softening the backing by moisture or heat or both, to render it sticky, folding the margins of the backing sheets and 5 of the covering 19 upon which they are superposed over the metal frame while the sizing is still tacky, and pressing the folded margins into place so that they will maintain their set upon hardening of the sizing. For this 10 purpose, the backing sheets 17 and 18 preferably consist of sized cotton cloth, either single or multiple, and the sizing ingredient may be waterproof or not, as desired. The sized cloth is flexible, yet self-sustaining and 15 without limpness, and in carrying out my process the backings are preferably moistened to make them more pliable and also to liberate the adhesive quality of the sizing, so that the backings may be suitably molded 20 over the metal ring 16 and will adhere together and to the outer covering 19 when dried. If the sizing is waterproof, the application of heat will ordinarily be necessary 25 to soften the backing; whereas, in case of glue-sizing, moistening alone will suffice for this purpose.

The reinforcing backing and covering constituting the box body are of such size and shape as to extend across an open end of the 30 ring 16 with their margins folded upwardly upon the sides of the frame to the opposite edge of the ring, and preferably over said edge and inwardly upon its inner face. When two backing sheets are employed, as 35 herein illustrated, the inner one may be smaller than the other so that its periphery terminates approximately at the upper edge of the ring, as indicated at 24 (Fig. 2); while the margins of sheet 18 preferably fold 40 over the edge of the frame and inwardly so that its periphery meets the body of the sheet at 25. It will be apparent, however, that the size of the backing may vary within wide 45 limits and that one or more such sheets may be used according to the desired thickness and stiffness of the box body.

The softened backing and outer covering may be applied to the metal frame by hand 50 operation or by suitable machines. As best results are attained by mechanical application and assemblage of these parts, I have indicated, somewhat diagrammatically, a type of apparatus which is suitable for the purpose, without intending to restrict my 55 process to the utilization of any particular mechanism which is commonly used for analogous purposes.

In carrying out my process with apparatus of the type shown in Figs. 5 to 7, the softened 60 backing sheets 17 and 18, preferably together with the outer covering 19, are superposed in proper order and placed upon an anvil 26 having an opening 27 defining the outline of the box section (Fig. 5). A die 65 or plunger 28 of similar outline then moves

downwardly to depress the central portion of the superposed sheets into the recess 27 and bend the sheet margins upwardly; and the ring 16 is inserted, as indicated in Fig. 6. The sheet margins which project above the upper edge of the ring are next turned inwardly over said edge (Fig. 7) by suitable fingers or other known apparatus (not shown), and a plunger 29 having a working face 30 of less area than that of the first plunger and having an annular shoulder 31 is brought downwardly to press and fold the inturned margins over the frame edge against the inner side of the ring and to compress the sheets of the body into adhesive union in their ultimate shape for drying. 75 80

These operations of the forming dies not only compress the superposed sheets, thereby causing the softened sizing to coat and penetrate the fibers of each sheet, and fold the margins thereof over the outer sides and upper edge of the frame, but also tend to stretch the material across the lower end of the metal ring so that, upon hardening of the sizing in the backing sheets, the sheet body is drawn taut over the bottom of the frame as well as adhesively united and stiffened by the dried sizing. The tautness of the backing sheets is accentuated by contraction of the sized fabric fibers which are stretched while moist and hence tend to shrink during drying; and this phenomenon is especially apparent when a water soluble sizing is employed in a soft and long-fibered fabric. 90 95

If the ring 16 is provided with the struck out tongues 20, the reduced end 30 of plunger 29 may have longitudinal grooves (not shown) in its periphery to receive the respective tongues so that they pierce the overlapped margins of the body. The hinge parts may then be applied to the completed box sections as shown in Fig. 2; an inner collar 32 may be applied between the display pad 15 and the wall of the box section 10; and the hinge parts may be covered by a fabric strip 33. 100 105 110

It is thus apparent that my improved method of forming a box section counts essentially in providing a frame defining the shape of the box, softening a backing sheet of sized fabric by moisture or heat or both, and folding the margins of the backing sheet over the frame and superposing an outer covering upon the backing while it is in a sticky condition. Although the covering is preferably applied to the backing before the latter is molded upon the frame, as previously described, it is obvious that it may be adhesively united thereto after the frame is backed and before the sizing dries out. The application of pressure is desirable in order to unite the backing and its covering and to draw the body taut across the frame and smoothly fold its margins over the frame edges, particularly when two or more back- 115 120 125 130

ing sheets are desirably united in juxtaposition; and the backing may desirably be subjected to heat, applied in any suitable manner during and after the shaping operations, if the sizing is substantially waterproof, or resistant to softening at low temperature, or if quick drying is desired.

The simple and easily practiced process herein described results in the production of a box section having the rigidity, durability and pleasing appearance of a section made by more complicated hand methods and of more expensive materials. It will be found that the backing becomes appreciably stiffer after the softening and rehardening of its sizing, especially when a plurality of backing sheets are stretched taut by the operation of shaping dies supplemented in some cases by shrinkage of the moistened fabric upon drying. The article may be constructed in a variety of shapes for particular purposes, and may be covered with any appropriate sheet material which will adhere to the sized backing. The completed box is light in weight yet strong and wear-resisting in use. The backing and covering are substantially inseparable from each other by reason of the penetration of the softened sizing into the fibers adjacent the backing under the pressure of the forming dies, and the overlapping margins of the stiffened backing effectively secure the body upon the frame without the necessity of special fastening means.

I claim:

1. A method of making a box section which comprises softening a sized backing sheet, and folding the margins of the sheet over a frame, so that the backing is affixed to the frame upon hardening.

2. A method of making a box section which comprises softening a sized backing sheet, folding the margins of the sheet over a frame, and applying an outer covering to the backing while the backing is soft, so that the covering is adhesively united to the backing and the backing is affixed to the frame upon hardening of the sizing.

3. A method of making a box section which comprises softening a substantially flat, sized backing sheet, superposing a covering sheet thereon, and folding the margins of both sheets over a frame before the sizing has hardened, so that the sheets are affixed to the frame upon hardening of the backing.

4. A method of making a box section which comprises softening a sized fabric sheet, stretching the sheet across the bottom of a metal frame, and folding the margins of the sheet over the top edge of the frame, so that the sheet is drawn taut and secured upon the frame upon hardening of its sizing.

5. A method of making a box section which comprises softening a sized fabric sheet, superposing an unsized covering sheet thereon, and concomitantly stretching the super-

posed sheets across the bottom of a metal frame and folding the margins of both sheets over the top edge of the frame before the sizing has hardened, so that the sheets are adhesively united and secured upon the frame when the sized sheet hardens.

6. A method of making a box section which comprises superposing a plurality of sized fabric sheets and an unsized covering sheet, softening the sized sheets, applying a metal frame edgewise upon the exposed surface of one of the sized sheets, and concomitantly pressing the sheets together and folding the margins of the several sheets over the sides and outer edge of the frame, so that the sheets are adhesively united and secured to the frame upon hardening of the sized sheets.

7. A box section comprising a frame defining the outline of the section, a sized backing applied across one end of the frame and having its margins folded over the outer sides and opposite edges thereof, and an outer covering superposed upon the sized backing and adhering thereto.

8. A box section comprising a flat metal frame defining the peripheral walls of the sections, a backing sheet of sized fabric applied across an open end of the frame and having its margins folded over the outer sides and opposite edges thereof, thereby to secure the backing upon the frame, and an outer covering superposed upon the backing and adhering thereto.

9. A box section comprising a flat metal frame defining the peripheral walls of the section, and a body consisting of a plurality of sized fabric sheets and an outer covering of unsized material adhesively united in superposed relation, the body extending across one end of the frame and having its margins folded upon the sides of the frame, the margins of the covering and of at least one of the sized sheets being folded inwardly over the opposite edges of the frame.

10. A container comprising a pair of similar sections, each having a flat metal frame defining its peripheral walls and a body consisting of a sized fabric sheet and an outer covering of unsized material adhesively united in superposed relation, the body extending across one end of the frame and having its margins folded over the outer sides and opposite edges thereof, and the frame having struck out tongues protruding through the folded margins, and a hinge connecting the two sections, the hinge having openings receiving the tongues of each section and the tongues being anchored in said openings to secure the hinge to the respective sections.

Signed by me at Attleboro, Massachusetts, this 12th day of June, 1930.

LESLIE WETHERELL.
